UNITED STATES PATENT OFFICE.

GEORGE E. MAYGER, OF ST. LOUIS, MISSOURI.

DESIGN FOR A PAPER-MOISTENING BRUSH.

SPECIFICATION forming part of Design No. 26,862, dated April 6, 1897.

Application filed February 1, 1897. Serial No. 621,564. Term of patent 7 years.

To all whom it may concern:

Be it known that I, GEORGE E. MAYGER, of the city of St. Louis, State of Missouri, have invented a new and original Design for Paper-Moistening Brushes, of which the following is a full, clear, and exact description, reference being had to the accompanying drawings, forming a part hereof.

Figure 1 is a plan view of a paper-moistening brush embodying my design. Fig. 2 is a side elevation of the brush shown in Fig. 1. Fig. 3 is a transverse sectional view taken approximately on the line 3-3 of Figs. 1 and 2 and looking in the direction indicated by the arrow.

The leading feature of my design for paper-moistening brushes consists of a brush having a woolly or spongy appearance and a handle attached to said brush, which handle consists of a sheet-metal plate doubled upon itself and forming a flaring opening between its ends, in which opening the brush is located, and forming a tubular portion at its center, the portions of said plate between said tubular portion and said flaring opening being in contact with each other.

The brush 5 has a woolly or spongy appearance, and when seen in plan view, as in Fig. 1, its free edge 6 is substantially straight, and when seen in elevation, as in Fig. 2, said free edge 6 is substantially oval.

The handle 7 consists of a plate of sheet metal folded upon itself, the center of said plate forming the tubular portion 8, which portion extends in a line parallel with the free edge 6 of the brush, and the rivet-heads 9 appear upon the sides of the handle, near

the tubular portion 8. The tubular portion 8 is nearly as long as the free edge 6 of the brush, and the portion 10 of the handle, which is between the tubular portion 8 and the brush, is reduced in width, and the side edges of said portion are segmental or curved. The elevations 11 are formed upon the sides of the portion 10 and extend at right angles to the tubular portion 8. The end of the portion 10 opposite the tubular portion 8 is somewhat wider than the length of said tubular portion.

The portions 12 and 13 of the handle are substantially rectangular in plan and are positioned relative to each other in such a manner as to form a flaring opening between said portions, and in which opening a portion of the brush is located.

The beads or elevations 14 and 15 are formed in positions parallel with the tubular portion 8 and between the portion 10 of the handle and the portions 12 and 13, and the rivet-heads 16 and 17 appear on the line which separates said portions 12 and 13 from the beads 14 and 15.

The material of the brush extends from between the portions 12 and 13 into the space between the beads 14 and 15.

I claim—

The design for a paper-moistening brush, substantially as herein shown and described.

In testimony whereof I affix my signature in presence of two witnesses.

GEORGE E. MAYGER.

Witnesses:

EDWARD E. LONGAN,
MAUD GRIFFIN.
